UNITED STATES PATENT OFFICE

BOWEN E. CLARKSON, OF KINGSTREE, SOUTH CAROLINA

LAMP HOLDER

Application filed April 29, 1930. Serial No. 448,305.

This invention relates to a device for holding lamp bulbs while they are being screwed into or out of their sockets. It is particularly useful in handling bulbs of street lamps, and of fixtures suspended from high ceilings.

It is an object of the invention to provide a device of this character which can be used in connection with bulbs of different sizes and can be readily pushed into or pulled out of engagement with a bulb without injuring it.

A further object is to provide a lamp holder which will tightly grip said bulb at any time so that it can be properly rotated.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawing

Figure 1 is a vertical section through the device, a lamp bulb being shown in position therein.

Figure 2 is a top plan view.

Figure 3 is a section on line 3—3, Figure 1.

Figure 4 is a bottom plan view of a supplemental support used with the device.

Referring to the figures by characters of reference, 1 designates a handle which can be of any desired length and secured to one end of this handle is a sleeve 2 which projects beyond the handle as shown, so as to provide an end socket 3.

Extending diametrically across the socket 3 through openings 4 formed in the wall of the socket are crossed arms 5 to the outer ends of which are pivotally connected gripping arms 6.

Extending from the upper ends of the arms 6 are deflecting fingers 7 connected by coiled springs 8 which are normally flat and

define a bulb receiving opening 9. Sleeves 10 of soft rubber or other suitable material are fitted snugly on the arms 6.

Under some conditions a supplemental supporting block 11 can be used. This block is preferably cylindrical and has a short shank 12 at one end adapted to fit snugly into the socket 3, this shank being formed with crossed grooves 13, so that when the shank is inserted into the recess 3 it can straddle the arms 6. That end of the block remote from the shank 12 can be formed with a depression as shown at 14. A cord 15 or other flexible device can be used for connecting the block 11 to one of the arms 5.

In practice the bulb to be handled is forced between the deflecting fingers 7 so as to stretch the springs 8. The bulb will be firmly gripped by the sleeves 10 and, if a small bulb is used the supplemental block 11 can be positioned at the end of sleeve 2 as shown so as to provide a seat at 14 for the bulb.

With a bulb positioned as described it can be readily raised to a fixture by means of the long handle 1 and rotated so as to screw thereto. Thereafter the device can be pulled off of the bulb without injury. Should it be desired to unscrew the bulb the foregoing operation would be reversed.

What is claimed is:

1. A device of the class described including a handle, arms radiating therefrom, gripping arms pivoted to the radiating arms, a relatively soft bulb engaging material extending around the arms, resilient connections between the arms for holding them normally converging, and supplemental bulb supporting means including a block, means for detachably connecting the block to the handle, and a flexible connection between said block and the handle.

2. The combination with a handle having a socket at one end and arms radiating from the handle and extending across the socket, of gripping arms pivotally mounted on the radiating arms, yielding means for holding the gripping arms normally pressed toward each other, a supplemental supporting block, and means on said block for insertion into the socket for rotation with the handle.

3. A device of the class described including a handle, gripping arms pivotally supported by the handle, resilient connections between the arms for holding them normally converging, and supplemental bulb supporting means including a block and means for detachably connecting the block to the handle.
- 5

In testimony that I claim the foregoing as my own, I have hereto affixed my signature.

BOWEN E. CLARKSON.
